UNITED STATES PATENT OFFICE.

MAURITZ C. INDAHL, OF PHILADELPHIA, PENNSYLVANIA, ASSIGNOR TO LANSTON MONOTYPE MACHINE COMPANY, OF PHILADELPHIA, PENNSYLVANIA, A CORPORATION OF VIRGINIA. TYPOGRAPHIC CASTING MACHINE.

Application filed March 3, 1928. Serial No. 258,981.

This invention relates to typographic casting machines for producing elements of printing forms such as types, and strip material, including printers' furniture. The principal object of this invention is to produce a machine for casting types, either those being type-high and bearing a printing face or those of lower height which are commonly called quads or spaces, and also for producing fused strips, the latter being either type high, such as rules or fancy borders, or of lower height such as leads, slugs or furniture, the type producing and strip producing being, if desired, automatically governed by the machine so that a combination thereof will cast material of any definite length and eject it from the mold of the machine without the necessity of cutting to accurate length.

Another object is to produce a machine capable of casting by the fusion process disclosed, for example, in United States Letters Patent No. 1,222,415, dated April 10, 1917, combined with casting by the non-fusion process disclosed, for example, in United States Letters Patent No. 1,257,006, dated February 19, 1918, such combination being productive of any desired length of material without cutting to length. Among other objects may be mentioned the production of a mold provided with a cross block to close one side of the mold when types are being cast, and, when strip material is being cast, to exert pressure on the partly ejected strip to hold it against movement during the casting of the next section of the fused strip material; governing mechanism for automatically controlling the movements of the mold blade so as to produce one or more fusion casts followed by a non-fusion cast or its equivalent; other objects will be hereinafter pointed out or will otherwise appear in connection with the following description of the embodiment of the invention illustrated in the accompanying drawings in which:

Fig. 1 is a front elevation of the machine, certain parts being broken away,
 Fig. 2 is a plan view of the same,
 Fig. 3 is a left end elevation,
 Fig. 4 is a right end elevation,
 Fig. 5 is an enlarged plan of the governing and driving mechanisms for the mold

blade, the mold being shown in horizontal section, 55

Fig. 6 is an enlarged plan of the right end of the machine, the mold being removed from its base and the galley pan being removed,

Fig. 7 is an enlarged vertical section on substantially line 7—7 of Fig. 2, 60

Fig. 8 is an enlarged vertical section on substantially line 8—8 of Fig. 2,

Fig. 9 is an enlarged vertical section of the mold in line with the blade and showing a first cast, 65

Fig. 10 is a section similar to that of Fig. 9 but showing several fused casts,

Fig. 11 is a vertical cross section of the mold in line with the material clamping device, 70

Fig. 12 is a perspective view showing the various parts of the mold in separated relation,

Fig. 13 is a section of the mold similar to that of Fig. 9 and of the micrometer stop 75 for the mold blade, the mold blade position being that for making small types,

Fig. 14 is a perspective view of the type shown in Fig. 13,

Fig. 15 is a perspective view of the stop 80 for mold blade connecting slide,

Fig. 16 is a perspective view of the mold blade connecting slide,

Fig. 17 is a view similar to that of Fig. 13 but showing the micrometer stop elevated, 85

Fig. 18 is a perspective view of a type shown in Fig. 17,

Fig. 19 is a perspective view of the mold blade and cores for producing hollow material,

Fig. 20 is a section on approximately line 20—20 of Fig. 5 showing the mold blade governing mechanism, 90

Fig. 21 is a longitudinal section through the setting drum of the governing mechanism on approximately line 21—21 of Fig. 20, 95

Fig. 22 is a cross section on approximately line 22—22 of Fig. 5,

Fig. 23 is a section on approximately line 23—23 of Fig. 5, showing particularly the 100 drive mechanism for the setting drum,

Fig. 24 is a section on approximately line 24—24 of Fig. 2,

Fig. 25 is a section on approximately line 105 25—25 of Fig. 24,

The machine illustrated has a hollow, box-like base 1 on which is mounted the main stand 2 on which is supported various mechanisms of the machine. The main stand 2 is stepped, the upper step 2' being toward the rear and supporting thereon particularly the mold and its control operating mechanism: the lower step 2" supports a bearing bracket 3. The general form of the machine is similar to that shown in United States Letters Patent No. 1,581,125, dated April 20, 1926. The bearings 3 support at intermediate points the mold blade lever 4, the pump lever 5, the matrix lever 6, the cross block lever 7, the holding plug lever 8 and the cut off slide lever 9. These levers are substantially vertical, their lower ends extending within the main stand 2 and being provided with cam rollers for contact with the respective cams 4', 5', 6', 7', 8', and 9', on the main shaft 10 suitably mounted in the main stand. The upper ends of these levers extend above the step 2" or the step 2' and are coupled with various devices to be operated by them as will subsequently be described.

The machine shown may be driven by the electric motor 11, which may be connected with a suitable speed device preferably mounted within the base 1. This device may be of any suitable construction, its purpose being to produce any desired speed for the main shaft, and the particular device shown is not illustrated in detail because it is of well known construction. In Fig. 1 its bearings 12 are shown, as well as its belt tightening adjuster 13 and its change speed control wheel 14. A chain 15 driven by this device suitably drives the worm shaft 16 which in turn drives the main shaft 10 by a worm and gear connection controlled by a clutch. This connection may be of any suitable kind: conveniently the worm gear may be mounted for loose rotation on the shaft 10 and may be provided with clutch teeth; opposing clutch teeth may be provided on a clutch collar splined to the shaft 10 and slidable thereon. As will be readily understood the sliding of the collar by the yoke lever 17 pivoted on the end casting 17' so as to engage its teeth with those of the worm wheel will cause the constantly rotating worm wheel to drive the shaft 10. The lever 17 is controlled by a handle 18 rotatably held in the right end bearing 3 and connected with the rod 19 by an eccentric pin 20 (Figs. 24 and 25). The left end of the rod 19 is connected to the end of the lever 17 and it will be readily seen that a slight turn of the handle 18 will throw the clutch into operative or inoperative position.

The mold is located on the right end of the top step 2' at which point a nozzle hole 21 (Fig. 8) is provided in the step 2', the top

stand being recessed as shown to provide space for the melting pot when swung and raised into operating position with its nozzle projecting upwardly through said hole 21. On the step is provided a rectangular block 22 serving as a base for the mold. This block is also provided with a nozzle opening 23 and a separable nozzle seat 24. Resting on the base 22 are two wearing plates 25, 25' (Fig. 6) separated from each other to form a longitudinal crack in which at the left fits the adjustable blade or abutment 26, one end of which extends over the nozzle seat to a position approximately at the edge of the metal injecting hole in the nozzle and the other end of which extends externally of the mold wearing plates to abut against the wedge 27 (Fig. 6) having steps 27' so that it may be adjusted crosswise of the mold to move the blade 26 and adjust it relatively to the nozzle hole. The right portion of the crack between the wearing plates is occupied by a cut-off blade 28 similar to the blade 26, the blade 28 being movable longitudinally from a position abutting the end of the blade 26 to a removed position opening a passage from the nozzle hole through the mold base structure just described. The cut-off blade or slide 28 is operated from the lever 9 in a manner to be hereinafter described. The blades 26 and 28 are substantially inverted T-shaped in cross section (Fig. 11) their broad base sliding on the top of the base block 22 and their vertical stem sliding between the proximate edges of the wearing plates 25, 25', the latter being cut away at such edges to accommodate the bases of the blades. The vertical stems are extended as at 26', 28' beyond the bases to slide over the nozzle plate (Figs. 9, 10 and 12) and the top surfaces of the stems are even with the top surfaces of the wear plates to form a smooth table on which the mold structure may be built. A ridge 29 on the base 22 and the clip 30 secured to the base block hold the wear plates in position with the abutment tightly held between them. The nozzle plate 24 is of a conical form and is seated in a recess in the block 22: the wear plates and abutment 26 and slide 28 are shaped to accommodate the nozzle plate and the extensions 26' and 28' slide over the top of the nozzle plate. When the slide extension 28' is moved to contact with the abutment extension 26' as shown in Figs. 9 and 10, the nozzle opening is, as is evident cut off and flow of metal into the mold cavity is prevented. When the slide 28 is opened, metal may flow into the mold cavity under pressure from the pump. The abutment and cut-off slide construction, it will be noted, is in general similar in purpose to that shown in Patent No. 1,581,125, previously mentioned. Secured upon the mold base structure are

the front cheek block 31 and the rear cheek block 32, the securing bolts 33 passing through large holes in the cheek blocks and being adapted to screw into the proper holes 5 of a series in the base structure, thus permitting a variable positioning of the cheek blocks. Between the cheek blocks are the type blocks, the rear type block 34 being of a single piece and the front type block, consisting of the main section 35 and the exit section or gripping piece 35'. The height of the type blocks is reduced controllably at 36 to form a matrix seat and the cheek blocks are beveled or cut away at 37 to provide a 10 space for the matrix and matrix holder or their equivalent. The cheek and type blocks and the point blocks are bound together by bolts 38 and the exit portion of the type blocks are maintained separated by a point block 39, the width of which depends upon the point size of the cast to be made. The 15 forward portions of the type blocks are separated by the slideable mold blade 40 above which is the point block 40'. The front cheek block 31 is notched or provided with an opening in its underside to provide for the cross block 41 which slides on the base structure with its side against the wall 42 of the notched block. This wall is located so that the cross block when extended across the mold cavity in closed or type casting position with its end in contact with the rear type block provides a side wall for the mold cavity which is properly positioned 20 with reference to the metal entrance or port provided between the wear plates and the abutment end 26' and the cut-off slide end 28'. The wall 42 is in the plane of the end wall 43 of front type block section 35 (Fig. 12). 25 The cross block is in sliding contact on its other side with the abutment block 44, also located in said notch and adjusted with reference to the cross block by screws in the holes 45. The block 44 is notched at 46 for the accommodation of the stepped end 46' of the type block section 35'. The inner, 30 wall of the section 35' and the inner end of the block 44 form an extension of the inner, mold cavity forming wall of the section 35. 35 The left end of the mold is provided with an abutment or squaring block 47 notched in its lower portion so as to bridge over the mold blade. The block 47 is provided with slots through which bolts project to adjustably secure the block to the ends of the cheek blocks. The lower portion of the abutment block extends below the plane of the wear plates so as to provide a space between the block 47 and the end of the base 40 structure of the mold. In this space is located the packing piece 48 having a flat top for supporting the wedge 27 previously mentioned and a ridge 48' for the wedge to back against. The front of the wedge 27 contacts, 45 as previously described, with the end of abutment 26. A mold blade forward stop 49 is secured to the block 47 beneath the blade 40. It will be seen that the mold cavity between the type blocks and the cross block may be adjusted longitudinally with respect 50 to the nozzle opening because of the enlarged openings through which the fastening bolts 33 extend, such adjustment of the type and cheek blocks carrying with it the abutment block 47 which in turn controls the position of the mold blade stop 49 and of the abutment slide 26 through the packing piece 48 and wedge 27. Of course, separate packing pieces of the desired size may be employed without the accompanying wedge as shown 55 at 48" in Figs. 9 and 10, where long casts or fusion casts are illustrated. The cheek and type blocks may be separated for any desired point size by employing the proper holes in the base 22 for the fastening bolts 33, the bolt slots in the abutment block 47 permitting of this adjustment. 60 The adjustment of the upper structure of the mold crosswise of the nozzle opening is accomplished by pushing this structure backward until the packing lugs 49' on the rear cheek block come into contact with the abutments 49" secured to the mold base (Figs. 5 and 12). It will be understood that the lugs 49' are interchangeable and the proper ones 65 are employed to position the mold selectively over the nozzle opening. This adjustment positions the cross block relatively to the nozzle opening and to the metal inlet port. 70 A friction clamp is located on the cheek block 31 to the right or exit side of the cross block and consists of a pin 50 slideable in a hole 51 in the cheek block, its inner end contacting with the type block section 35'. A bracket 52 secured to the front face of the cheek block forms a pivot for a bell crank lever 53 having a short, depending arm for contact with the outer end of the pin 50 and a long, horizontal arm to which power is applied and relieved in timed relation to the various functions of the machine to cause 75 the pin to press against the type block section or gripping element 35', and thus grip the material already cast and not yet ejected entirely from the mold, the gripping being applied when the material is not in motion 80 and the releasing being when the material is in the act of being ejected further toward the exit end of the mold. The gripping is facilitated by the element 35', being grooved as at 52' to give a spring effect and being provided with a slight gripping lug 53' of small dimensions, said lug being wedge-shaped to allow the cast type or strip to be readily advanced by the ejecting action of the mold blade, and said lug being adapted to be tightly forced against or into the cast by 85 action of the lever 53 and pin 50. 90 The mold blade 40 may be solid but as shown it is made up of various parts shown 95 100 105 110 115 120 125 130

separated in Fig. 19 and assembled in Fig. 12. The mold blade shown is adapted to the making of hollow types and strips, such as the hollow types 54 and 54' shown in Figs. 14 and 18 respectively and the fused strip 54" shown in Fig. 10. These typographic elements are of usual outside size and dimension and are provided with two hollow spaces separated by a vertical rib. These spaces are formed by the blade cores 55, 55' each provided with a depending lug 56, 56' which contact with the packing piece 48 on one side and the stop 49 on the other side. The cores are thus maintained immovable and are of such length as to project into the mold cavity, their ends being in the neighborhood of the cross block, one core being on one side of the inlet port and the other on the other side thereof. The movable members of the blade shown are the central slide 57 between the cores and the rear slide 58 and the front slide 59. The slides 58 and 59 are channel shaped and are assembled on edge and in contact, with each other, the channels being toward each other; the outside height of each slide corresponds to the body height of the material to be cast and their combined width to the point size of such material. The cores are placed, each in its channel and the height of the cores is equal to the inside height of the channels. The central slide 57 fits between the cores and takes up all the channel room therebetween. The cores as shown are sloped at the top and the slide 57 is wedge-shaped at the upper portion to fit said slopes. The lower floor of each channel piece is notched at 60 to allow the core lugs 56, 56' to project below the compound blade and the notches are lengthened to permit of sliding of the channel and central members on the cores. The movable members are longer than the cores and extend clear of the mold at which point there is provided in the lower surface of the channels 58 and 59 a stop lug 61 to come against the relatively fixed stop 49 in arresting the forward movement of the blade. The central member 57 is caused to move with the channel members because of the tapered pin 62 passing through holes 63 to tie the movable members together and cause them to move as one.

The assembled blade is placed to slide on the mold base structure, the core lugs 56, 56' being between the packing piece 48 and the forward stop 49. The cores are thus raised above the surface of the mold base so that metal may flow around them. The ends of the movable members 57, 58 and 59 form an end wall of the mold cavity, these parts having a metal tight, sliding fit around the cores and also with the bottom of the mold cavity over which the channel edges slide and with the type blocks 34 and 35 in contact with which the outside sides of the channels 58 and 59 slide. The outer end of the compound blade is provided with a depending lug 64 providing a notch for connection to the mold blade driving mechanism. The cheek blocks 31 and 32 are water cooled, there being provided bores in each block independently and shown dotted in Fig. 5 to which water is supplied and drained through a piping system 65. The pipes are easily detachable from the cheek blocks and the drain pipes discharge into the basin 66 (Figs. 1 and 3) from which the water is discharged by suitable piping.

The operation of the mold blade is accomplished from the lever 4 previously mentioned, the upper end of which is connected to the short arm of the bell crank lever 67 pivoted parallel with the upper platform 2' by the bolt 68 by means of the spring box link 69: this link is provided with springs in a well-known manner so as to yield in both directions of travel of the lever 4. The bell crank has its long arm connected by the link 70 to the tong lever 71, the opposite end of the lever 71 being pivoted by the bolt 72 to the adjustable carrier 73. The lever 71 is connected centrally by a link 74 to the central point of the tong lever 75, one end of which is pivoted at 76 to the free end of compensating lever 77 and the opposite end at 76' to the mold blade connecting slide 78 (Figs. 5 and 16) the right end of which is provided with an upstanding lug 79 to couple with the lug 64 on the mold blade 40 so as to cause the mold blade to reciprocate with the slide 78. The compensating lever 77 is pivoted at 77' and swings to permit the slide 78 to move in a straight line. It will readily be seen that the reciprocations of the lever 4 are transmitted through the levers and links mentioned, to the mold blade. With the lever 4 pulled away from the top stand the mold blade will be withdrawn to the left of the metal entrance of the mold, as shown in Fig. 5; when pushed toward the top stand, the parts will be as shown in dot-and-dash lines in Fig. 5. The stroke of the mold blade, it will be observed, is increased somewhat over that of the upper end of lever 4. The rear stop of the mold blade is the right end of carrier 73 as shown at 73' (Fig. 15) against which surface the left end of the blade abuts. The adjustable carrier 73 is shown clearly in Fig. 15. It is provided with a vertical slot in which the raised rear end 80 of the mold blade slide 78 slidably fits as shown in dotted lines in Fig. 15. The surface 81 of this slide may come against the end wall 82 of the slot in the member 73 to act as a stop. The lower section of the slide 78 seats in a groove in the under surface of the adjustable stop 73. A hole 83 in the member 78 serves for the pivot 76' of the tong lever 75. Similarly a hole 84 in the

adjustable carrier 73 serves for the pivot bolt 72 of the tong lever 71.

On the left end of the portion 2' of the main stand 2 is secured a bracket 85 having a horizontal top portion suitable for slidably supporting the adjustable carrier 73: a top plate 86 above the carrier holds it in contact with the bracket. The bracket may be extended rearwardly, as shown, to serve as a support for the bell crank pivot 68 and the compensating lever pivot 77'. It also acts as a bearing for the lower surface of slide 78. In front of and parallel with the member 78 the stop 73 is provided with a recess for the reception of a coiled compression spring 87, also held down by the plate 86. A lug 88 riveted to the underside of the plate at its right end confines the spring at one end, while the other end comes against the shoulder 89 forming the end of the spring recess. The opposite side of the shoulder is cut at an angle and is provided with a hardened wear pin 90 (Figs. 13 and 17). It will be seen that, since the lug 88 is stationary, the action of the spring will cause the member 73 to slide to the left.

Opposing the wedge face of the pin 90 is the correspondingly angled face of the wedge 91, the opposite, vertical face of which contacts with a slotted, fixed block 92 held by a cylindrical casting 93, secured to the bracket 85, the wedge and the block 92 being within the cylinder. The wedge is held laterally by forked projections 89' of the carrier 73 with the slot sides of block 92. The top, horizontal end of the wedge is adapted to contact with the screw 94 screwthreaded in the top of the casting 93. On the upper end of the screw is the operating handle 95 and below it is the scale ring 96 clamped so as to be rotatable with the screw. Turning the handle one way moves the screw to push against the wedge 91 and force it downward, thus moving the carrier 73 to the right: turning it the other way allows the wedge to move upward due to the spring 87. In any position of the screw 94, it may be clamped by turning the set screw handle 97 the set screw 98 of which is threaded through the side of the casting 93, and has a shoe 99 at its inner end for locking engagement with the screw 94, in an obvious manner. The casting 93 is provided with a vertical bore in which is provided the pica pin 100, the upper end of which is hooked to the periphery of the scale ring 96, so that rotary movements of the latter will cause the pin to slide up or down in the bore. The pin and bore are angularly positioned as shown in Fig. 5 so as to be easily seen by the operator and the pin is provided with zero marks 0, 1, and 3 to be read in conjunction with the pica scale 101 secured to the casting 93 at one side of the pica pin 100 and shown diagrammatically in Figs. 13 and 17. The skirt of scale ring 96

is marked into points and fractions thereof which are readable with reference to a vertical zero point placed on the pin 100 where it slidably contacts with the ring 96. In practice either 0, 1, or 3 on the pin 100 are used as zero points depending upon whether packing piece 48, 48" is being used, there being provided three sizes of such packing pieces. A single turn of the wheel 95 will raise the pin 100 a half-pica on the scale 101. It will be seen that the carrier 73 may be adjusted by accurate micrometer measurement to picas; points and fractions of points, this adjustment locating the rear stop surface 73' for the mold blade stop end 64'. Thus the forward end of the mold blade 40 may be accurately positioned on its rearward or mold-cavity dimensioning stroke so as to provide a cavity of definite length. The normal forward mold blade stop, as has previously been stated, is the block 49 or an interponent coming between that block and the forward face of the depending lug 61 on the mold blade 40; although for very short casts the surface 81 of the mold blade slide 78 coming against the slot end 82 of the carrier 73.

The pump mechanism is operated from cam lever 5 connected at its upper end with a rod 102 extending downwardly and rearwardly through windows in the stepped portion of the main stand, its lever end being pivoted to the pump bell crank 103 (Figs. 3 and 7) pivoted to the main stand. The connection between rod 102 and lever 5 consists of a slotted head 104 and binding handle 105 such that when the handle is pushed down the lever will oscillate idly in the slot and when the handle is pushed up the rod and lever are bound together to cause the lever to move the rod and actuate the pump. The construction of this hand-controlled connection is substantially as shown and fully described for the material making machine disclosed in Letters Patent No. 1,581,125, previously mentioned. It will therefore be unnecessary to describe it in detail herein. The pump and metal pot and associated parts are, as shown, generally similar to the corresponding parts of the machine of the above patent and to the type casting machines manufactured by Lanston Monotype Machine Company and the operation of the machine as a whole is similar to that of such well known machines. It will therefore be unnecessary to describe the mechanisms referred to, in detail, reference being had to the above patent, although certain identifying parts may be pointed out; for example, the piston lever operating rod 106, the swing frame 107, the latch device 108, the pot 109, the pump body 110, the piston 111, the piston lever 112, the pot raising screw and handle 113, all of which are

of well known construction. The pump and pot are adapted, as usual to be swung to position the nozzle 114 under the nozzle plate 24 and to be raised to seat against the under side thereof so as to force metal into the mold cavity. The piston stop 115 (Fig. 8) is of somewhat strengthened construction, as shown, and a non-return valve 116 is provided in the metal inlet below the adjusting screw 117, the usual hat-valve below the piston being dispensed with.

The cross block 41 is provided with a tongue and groove end 118 into which hooks the lug 119 secured by a screw 119' to the head 120 pinned to the end of the hollow slide 121 slidably mounted in the forward projecting arm 122 of the bracket 123 secured to the step 2" by screws 124 and provided with an upwardly extending arm 125 to be referred to hereinafter, and with a vertical face 126 against which the mold base 22 abuts for positioning the latter. The slide 120 has bearings in the inner and outer ends of the arm 122 and the latter is bridged over the central portion of the slide and is open from below. The central portion of the slide is screwthreaded externally for the reception of a nut 127 against the inner face of which the forked upper end of the lever 7 may contact to move the slide outwardly and thus withdraw the cross block 41. The head 120 is pressed again by one end of the spring 128 coiled within the hollow slide, the other end of the spring contacting with the screw plug 129 in the outer end of the bracket arm 122. It will be seen that the cam 7' for lever 7 moves the upper end of said lever against the nut 127 and thus moves the slide against the force of the spring 128. When the cam allows the lever to move back, the spring will cause the slide to move inwardly. Thus the cross block 41 reciprocates to a closed position in which its inner end contacts with the extended inner wall of the rear type block 34 to a withdrawn position, shown in dot-and-dash lines in Fig. 5, in which the advancing type clears the end of the cross block. When fused increments are being cast into a strip, it may be that the block 41 cannot advance to its closed position under the influence of the spring 128, being prevented by the type or element being in its path. In this case, the spring forces the end of the block against the type metal cast and grips it during the casting of a subsequent increment. This gripping is in addition to that provided by the pin 50 and gripping element 35' and is particularly important or necessary when the element being cast does not extend far enough beyond the cross block to come under the influence of the gripping part 35' and its lug 53'. This condition is frequently met with especially when short increments are being cast. The left

side wall of the cross block is extended to form the pressure lug or step 130 of decreased area to ensure high pressure against the type block 34, and a firm seating against the type block 34 to prevent leakage of metal 70 between these parts. There are also provided gripping ridges 131 in the end of the cross block, these ridges or points extending slightly beyond the lug 130 and to the right thereof, to grip into or against the metal 75 cast and to make a more positive gripping action than if the end of the block were not provided with these projections. When the cross block is in closed position these ridges 131 are adapted to extend into the groove 80 132 provided in the type block 34.

The lever 53 for operating the pressure pin 50 is operated from cam 8' by lever 8, (Fig. 24) which is a bell crank lever pivoted at 133 on the bearings. Its lower arm contacts with the cam 8' and its upper arm extends inwardly toward the step 2' of the main stand. The end of this upper arm is connected to a vertical rod 134, the upper end of which is adapted to contact with the 90 lower face of the lever 53. The upper portion of the rod is provided with a slot 135, through which extends a bolt 136 secured to the vertical arm 125, previously mentioned, of the bracket 123. The slot and bolt connection holds the rod 134 in proper position and allows it to slide up and down. The outer end of lever 53 is connected by a tension spring 136' to a pin on the bearing 3 or on the lever 53 in proximity to this bearing and this spring serves to maintain the pin 50 pressed against the grip element 35' at all times except when the lever 8 and rod 134 are pressing the lever 53 upwardly sufficiently to relieve the pin 50 of the spring 105 pressure. The operation of this mechanism will be readily understood and the fact that the cam 8' is shaped and the mechanism timed to produce a gripping effect while there is no motion of the cast and a releasing effect 110 when the cast is being moved toward the exit of the mold.

The cut-off slide 28 and its extension 28' are operated, as previously stated, from cam 9' and lever 9. The latter is pivoted at 137 115 to bearing 3 and its upper end is forked and provided with a pivotal bolt 138 extending across and between the forks. A rod 139 extends through this bolt between the forks, the front end of the rod being provided with 120 adjustment nuts 140. The rod 139 extends horizontally toward the rear of the machine and its further end is pivotally connected to the arm of the bell crank lever 141 which extends generally parallel to the slide 28. 125 The bell crank is pivoted at 142 to a fixed part of the machine and the end of its rearwardly extending arm is provided with a bearing surface for contact with the end of a sliding piece 143. This piece slides in 130

bearings in the galley bracket 144 bolted to the end of the step 2' and having a horizontal table portion for the support of the galley. The piece 143 is provided with a hook 143' to coat with a notch 143'' in the slide 28, said hook lying above the lever 141. As the bell crank rocks on its pivot the slide 28 is moved toward or away from the end of its associated abutment 26, the side moving of course, in a straight line because guided between the wear plates 25, 25'. The bell crank is preferably pivoted to the bracket 144 and the bell crank and piece 143 are covered by a plate 144'. The table portion of the galley bracket has a screw-threaded aperture for the reception of a rod 145, the right end of which lies near the right end of the galley bracket and the left end of which extends in proximity to the right end of the slide 28. The rod may be turned to cause said left end thereof to be positioned toward or from the slide 28; in its adjusted position it may be fixed by the lock nut 146. Between the screwthreaded portion of the rod and its left or inner end a collar 147 is provided and at the left of the collar, the rod supports a coiled spring 148, one end of which comes against the collar, the other end of the spring is seated in a recess in the sliding piece 143, the left end of which abuts the bearing end of the bell crank 141. The spring 148, as will be seen, tends to force the slide 28 to the left into closed position against the abutment 26 and the force of the spring may be varied by adjusting the rod 145. The operating cam 9' is shown in Fig. 24: it will be seen that it has a gradual incline 150, a short dwell, 151 and a sudden drop at the point 152. As the shaft 10 turns the action of the cam is to effect a pull on the rod 139 which in turn will cause the bell crank to open the slide 28, the latter being kept open for the cam dwell and then closed suddenly by the letting go of the cam at the point 152 and the consequent quick release of the spring 148. The cam 9' is cut away behind the dwell 151 to form a spring end and the lever 9 is provided at its lower end with a similar spring so that in case the shaft 10 should be operated accidentally in a direction opposite to its normal rotation, these springs will take up the shock and prevent breakage of the lever 9. The action of the closure slide must be quick in closing and to prevent excessive noise a leather washer or other suitable damping device 153 is held on the rod 154, the other end of which rod is connected to the lever 9 at the point 155. When the spring acts, the lever 9 is pulled inwardly by the rod 139 and this causes the damping device to come suddenly against the vertical web 156 of the galley bracket 144, nuts being provided and the rod 154 being screw-threaded so that the damping device may be 65 adjusted accurately to function best. The amount of opening of the slide 28 may be adjusted, as is obvious, by suitable manipulation of the nut 140. The abutment 26 may be positioned, as before described, by 70 the wedge 27 or its equivalent. Therefore the position of the metal entrance slot or port determined by these slides 26 and 28 may be adjusted relatively to the cross block and to the nozzle opening and the length of 75 the slot opening may also be varied as desired.

The matrix is moved up and down as is usual in type casting machines of the kind illustrated, so as to be seated to form the 80 top of the mold cavity, upon the type blocks, the cross block or its equivalent and the mold blade. The arm 125 of the bracket 123 extends upwardly in forked form in front of the mold and is provided with horizontal 85 openings for the reception of the pivot pin 157 extending substantially parallel with the mold blade. Supported on this pin is the V-shaped bridge 158, which passes horizontally over the mold, its pointed end being 90 provided with a vertical eye through which the standard 159 extends. This standard is screwed into the step 2' and rises vertically behind the mold. Its upper end is screw-threaded and is provided with two nuts 160, 95 160' between which passes the cross pin 161 which pierces the eye of the bridge 158 and extends substantially parallel with the pin 157. It will be seen that by manipulating the nuts 160, 160' the bridge may be raised or 100 lowered to provide a fine adjustment, while, upon removing the upper nut 160', the bridge and its associated parts may be raised on the pivot 157 to provide a clear space above the mold and facilitate mold replacement, adjustment and the like. A raised position is shown dotted in Fig. 4. The bridge 158 is provided with an upwardly extending boss 162 approximately immediately above the mold cavity, this boss being pierced laterally to provide bearings for the shaft 163, centrally on which is carried the pinion 164. The boss is recessed to provide space for this pinion and its top is domed over the same to provide a cover therefor. The boss is also 115 pierced at right angles to the shaft 163 below the pinion 164 and slidably supported in the opening thus provided is the rack 165, the upwardly extending teeth of which mesh with the teeth of the pinion. This rack is operated from the lever 6, the lower end of which is driven back and forth by the double acting cam 6' and the upper end of which is connected with the rack. This connection consists primarily of the rod 166, one end of which is pivoted to the rack at the point 167 and the other end of which slides through the pin 168 extending across the forked

upper end of the lever 6. In front of the lever, the rod is provided with a nut 169 and between the nut and the pin 168 is a collar 170: thus, when the lever reciprocates forwardly, away from the mold, the rod is positively pulled in the same direction. On the other side of the pin 168, the rod is provided with a loose collar 171 and between this collar and a nut 172 screwthreaded on the rod in proximity to the pivot 167, the rod is surrounded by and supports a coiled spring 173: thus, on the reciprocation of the lever toward the mold, the pin 168 pushes against the collar 171 and compresses the spring 173 which in turn moves the rod 166 by yielding pressure toward the mold. The movements of the rod and the rack 165 turn the pinion 164 and its shaft 163. The latter is at each end provided externally of the boss 162 with an eccentric pin extension 174, the two extensions being in line and each pin supports a depending strap or rod 175, the latter having bearings on the pin extension. The lower ends of these straps are pivoted by the pin 176 to a matrix support 177, vertically slidable in the matrix guide 178. The latter has a horizontal platform 179 which is seated on the rear cheek block 32 of the mold and a vertical portion which has side rails 180 to form a groove for the reception of the sliding portion of the matrix support 177: the opposite side of the groove is covered by a plate 181 secured to the rails 180 and closing the groove in which the part 177 slides. The table 179 is bolted to the rear cheek block by suitable bolts in large apertures and is positioned lengthwise of the mold cavity by bringing its left end face against the squaring block 47 which extends upwardly above the cheek blocks for this purpose. A fine adjustment to locate the matrix in proper relation to the mold cavity may be had by the adjustment of the screws 182, (Figs. 9 and 10) or their equivalent. The cross-wise adjustment of the matrix guide 178 is accomplished by bringing the front face of the platform 179 against the point block 40' which is of sufficient height to answer this purpose. The cheek blocks and the type blocks are cut away to provide space for the vertical part of the matrix guide and for the matrix support, the vertical, sliding portion 177 of which has been referred to. The lower portion of this support is in the form of a hollow box (the bottom of which is open and is in close proximity to the top of the mold cavity when the support is in lowered position. This box extends to the right of the vertical slide 177 and has vertical side walls and angularly sloping top and bottom walls 183 and 184, the top of the box at the right of the portion 177 being open. Thus, there is formed an angular

chute into which the matrix holder 185 may be slid so that the matrix 186 held by it may extend through the bottom of the support and rest, in the lowered position of the support, upon the type blocks, the mold blade top and the cross block or its equivalent. The matrix is pressed upon these parts with sufficient force to hold it against the pressure of the molten metal forced into the mold cavity by the pump. It will be understood that the matrix is forced down by the pressure of the spring 173 acting in the manner previously set forth. When the rod 166 is pulled forwardly by the lever 6, the rack 165 and pinion 164 cause the pins 174 to pull the matrix supporting mechanism including the matrix holder and the matrix to raised position in which the cast metal may be ejected from the mold cavity without interference from the matrix. The matrix holder is in the form of a block to fit the matrix support box, having a shoulder 187 to locate the holder in the box by having this shoulder come against the top wall 183, (Fig. 9). Its lower surface is substantially horizontal and is provided with a cross recess into which the matrix is seated, the matrix and recess being tongue-and-grooved to cause the holder to support the matrix. The groove extends across the lower surface of the holder so that when the holder is removed from the support, the matrix may readily be slid out and another placed in the holder. The block 186 is also provided with an end recess 188 for the reception of the lower end of the handle 189 which is pivoted to the block by the pin 190. The upper end of the handle extends externally of the support box and an intermediate portion is provided with a cam lug 191, the cam surface of which is adapted to work against the pin lug 192 seated in the lower wall 184 of the box, when the handle is depressed manually. It will be seen that the holder may be inserted into the box through its top opening and pushed down until its shoulder 185 comes against the wall 183, whereupon the handle 189 may be depressed to force the lug 191 in front of the pin 192 to lock the holder to the support. Lifting the handle up to release this lock allows the holder and its matrix to be removed. This construction permits very ready exchange of matrices and the insertion and withdrawal of the holder being at an angle both to the vertical movement of the support and to the horizontal discharge movement of the cast product, make such exchange of matrices possible without disturbing any of the mechanism of the machine. In case a blank matrix is used and it is not necessary to lift it from the mold, the collar 170 is removed from the rod 168, so that the forward reciprocation of the lever 6 has no effect.

It will be readily apparent to those

skilled in the art that the mechanism shown and described is useful for producing single types or fused strips, the former being cast in a cavity the ends of which are closed by the mold blade and the cross block positioned with its end against the rear type block (Fig. 9), the latter being cast between the mold blade and a previous cast or a bait inserted from the exit end of the mold (Fig. 10), the cross block being withdrawn in this case and preferably its end being forced, during the casting operation, against the side of the strip or bait to hold it against the rear type block and prevent its displacement by the casting pressure. In practice the use of a bait is unnecessary when the construction shown is employed because the first cast may be a type and the next cast may be fused to it and this process repeated to form a strip of indefinite length. In casting types the mold blade ejects the type beyond the cross block so that the latter may be returned to closed position for the casting of the next type and in this case the forward stop for the mold blade is the stop 49 against which the lug 61 of the mold blade abuts. For fusion casting, the ejection should be slightly beyond the entrance slot for molten metal so as to ensure fusion and in this case the cross block may not return to closed position but presses against the partially ejected cast, and to provide for this lessened stroke of the mold blade, an interponent 193 is placed between the lug 61 and the stop 49, the length of this interponent being such as to properly position the end of the partially ejected cast so as to cause fusion with the next injected molten metal. When the mold blade makes such a fusion stroke its forward end advances to a definite position controlled by the interponent 193 its position is short of the mold cavity forming wall of the cross block by a fixed amount, say, two picas. When it retreats to the point fixed by its back stop, it leaves a cavity equal in length to the length of its stroke: the first cast, however, is against the cross block and the cavity for this first cast is two picas longer than the subsequent cavities. The first cast is therefore two picas longer than subsequent casts. It will be seen that to cast a length of definite amount, two picas should be subtracted from that amount and the result divided by the standard fusion stroke length, say five picas or not more than six picas, thus obtaining the number of strokes: if there is a fraction left over, the standard stroke length may be varied by manipulating the micrometer wheel 95 of the back stop to produce the length of strip desired. (Example: 45 picas minus 2 equals 43 divided by 5 equals 8 strokes, and a remainder of 3 picas or 36 points divided by 8 equals 4½ points to be added to each stroke). For the forward stroke after the first cast the interponent 193 is raised to active position, for the following fusion strokes the interponent is also in action; after the final cast it is removed to allow the completed strip to be ejected from the mold and the cross block to close, the process being repeated for the production of subsequent strips.

The control of the interponent is automatic in the machine shown. Secured to the bracket 85 by screws 194 is the cylindrical drum holder 195, the axis of which is parallel to the mold blade. A portion of the cylinder is cut away to expose the drum 196 loosely journaled pieces being secured to the ends of the holder by screws. The axes of the end pieces are provided with apertures to act as journals for the shaft 199 which extends through the pieces 197, 198, and beyond them. To one end of the shaft 199 is journaled the lever 200, this lever projecting downwardly and rearwardly and bearing on its end the interponent 193 previously mentioned, the interponent being slidable thereon in the direction of movement of the mold blade. The lever is normally held with the interponent in its uppermost position in which it comes between the stop 49 and the path of the stop 61 on the mold blade. It is thus held yielding by the spring 201, one end of which is secured to the lever and the other, by the pin, 202 to the drum holder 195. The lever 200 is also provided with an operating pin 203 extending toward the interior of the drum parallel to the shaft 199, through a slot in the end piece 198. The shaft has pinned to it the radial lug 204 which extends radially from the shaft sufficiently to come against the pin 203 and press it downwardly to cause the lever 200 and the interponent 193 to move to its lowermost position in which it is out of the path of movement of the blade stop 61. The drum 196 is provided internally with a setting lug 205 which projects toward the shaft so as to come against the lug 204. The manual rotation of the drum thus causes the lug 205 to set or position the lug 204. The shaft 199 is surrounded by a coiled spring 206, one end of which is fastened to the lug 204 by the pin which secures the lug to the shaft and the other end of which is fastened to the end piece 197 by the pin 207 (Fig. 22). When the drum is rotated from its normal position shown in dot and dash lines, Fig. 22, so as to cause its lug 205 to move the shaft by 204 and thus turn the shaft, the spring 206 is tensioned. The drum is peripherally provided with teeth 208 with which cooperate the locking pin 209 normally spring pressed between adjacent teeth of the series 208 and capable of

being withdrawn by the handle 210, this locking pin connection being of any desired kind and being housed in a radial boss 211 in the end piece 198. It is obviously necessary to withdraw the pin 209 to allow of the turning of the drum, which after being positioned is locked in place against turning back because of the tension of the spring 206, by letting the pin 209 snap back into locking position. The drum, if turned far enough, will cause its lug to move shaft lug 204 into contact with and act upon the pin 203 to move the lever 200 and its interponent 193 in lowermost position. If the drum is locked in this position by the locking pin 209, the mold blade will at each stroke come against the forward stop 49 and the cross block will after each cast take up its closed position. Thus the machine will cast individual types each stroke. If locked short of this position the drum will set the shaft lug 204 short of the operating pin 203 so that one or more fusion strokes of the mold blade (those stopped by the interponent) will take place before the lug 204 moves the pin 203 to remove the interponent. To move the shaft a definite amount for each mold blade stroke, a pawl and ratchet driving mechanism is employed. The ratchet wheel 212 is mounted on the shaft 199 outside of the end piece 197. The ratchet wheel is provided with an inwardly extending boss or collar 213 which is slotted in its end to accommodate the driving pin 214 which pierces the shaft inside the drum. Thus, the turning of the ratchet wheel causes the shaft to turn. Mounted loosely on the end of the shaft is the lever 215 having a pawl arm 216 near the end of which is pivoted the pawl 217 in position to engage with the teeth of the ratchet 212. The lever 215 extends downwardly and at its end is connected by the rod 219 to the pump bell crank lever 103. The rod 219 extends substantially parallel to the rod 102 (Fig. 7) and is provided with a spring 220, arranged in an obvious manner to cause the pump lever 103 to yieldingly drive the pawl lever 215 and to positively move it in the other direction. A spring 221 mounted (Fig. 23) adjacent the end piece 197 is adapted to press the pawl tooth yieldingly against the ratchet wheel teeth. At each stroke of the pump, it will be seen, the pawl 217 will move the ratchet wheel 212 one tooth thereof and cause the shaft to rotate a definite amount. This, as has been said, will cause the lug 204 to move away from the drum lug 205 toward the operating pin 203 and eventually to move the latter and withdraw the interponent. If the drum has been positioned to bring the lug 204 against the pin 203, then one stroke of the pump and of the mold blade will withdraw the

interponent. For releasing the pawl the bell crank lever 223 is provided. This lever is pivoted to the end piece 197 at 224 and its pawl engaging arm extends upwardly near the tail of the pawl 217. An arm 225 on the pivot 224 is engaged by one end of the pawl spring 221 to hold the lever 223 away from the pawl. Another, horizontal arm 226 on the pivot 224 may be moved upwardly to turn the levers 225 and 223 and cause the latter to hit against the tail of the pawl and withdraw its tooth from the ratchet. When this is done, the spring 206 obviously turns the shaft 199 back until the lug 204 comes against the drum lug 205 as set and the release of the lever 226 will allow the pawl to act again in repetition on the ratchet teeth. A cam lever 227 pivoted at 227' to the end piece 197 may be rotated by hand to act against the lever arm 223 and the pawl tail to hold the pawl permanently out of working contact with the ratchet so that all pump strokes will be ineffective in operating the ratchet and in influencing the position of the interponent.

The lever 223 is adapted to be operated automatically. Its arm 226 extends above the plate 86, the end of the arm being provided with a setting screw 228, the lower end of which is just above the lever 229 (Fig. 13) pivoted at 230 to a standard 231 rising upwardly from the element 73. The left end of the lever 229 rests on said element 73 and its extreme end 232 is cut away to leave a space between it and the element 73, there being provided a cam surface 233 between the lever proper and its end 232. The mold blade connection 78 is provided on its upper surface at its left end with a block 234 one end 235 of which projects laterally therefrom above the element 73 and under the lever end 232. The portion 232 is of sufficient length so that the end 235 does not reach to the cam 233 in the forward sweep of the mold blade and its connection 78 when the interponent 193 is raised to active position. When, however, the interponent is lowered, the connection 78 moves to the right a sufficient distance to engage the cam 233 and thus raise the lever 229 on its pivot and cause its end 232 to engage with the lever arm 226 and raise the latter, thus causing the pawl 217 to be disengaged from the ratchet wheel. This automatically restores the lug 204 to the position against the lug 205 by action of the spring 206, such position being the set position of the drum 196. Such resetting, it will be seen, provides for a repetition of the casting operations necessary to produce the strip for which the drum was set. It will be observed that the interponent 193, coming between the stop 49 and the mold blade lug 61, acts as a stop for the mold blade lug 61, the shock of such stop-

ping being transmitted to the stop 49 which is fixed with reference to the upper structure of the mold. It is clear that the interponent and its supporting arm may be made 5 rigid so as to take up this shock without aid from the stop 49; therefore the interponent is in nature a stop and is to be regarded as a stop to arrest the forward stroke of the mold blade even though termed an interponent. Since it acts as a stop when the 10 mold blade forward stroke is shortened to provide proper positioning of the cast for fusion to the next cast, the interponent may be considered as a forward fusion stop, the 15 fixed stop 49 being regarded as the long stroke or ejection stop. The particular construction of the interponent shown has the advantage of accommodating itself to the adjustment of the mold upper structure and 20 the stop 49 carried thereby, and the interponent stop needs therefore no independent adjustment.

In the operation of the machine, the mold base is properly located on the step 2' with 25 its forward edge drawn against the bracket 123 and the mold superstructure is then placed thereon. This superstructure may be assembled on the bench and consists particularly of the type, cheek cross and point 30 blocks, the mold blade and the squaring block and on this structure may be mounted the matrix guide 178 with its plate 179 against the point block 40' and longitudinally set by the screws 182. The superstructure is set on the mold base and positioned 35 against the abutments 49" and the squaring block against the selected packing piece 48. The mold blade and the cross block should be hooked to their driving devices during this 40 assembly. The matrix bridge may now be tilted to place and the straps 175 connected to the matrix support 177; the matrix and its holder may now be inserted in the support and locked and the positioning of the matrix 45 adjusted by manipulating the nuts 160, 160'. The mold blade back stop should be adjusted and the setting drum turned to the desired number of casts; the pot may be swung in and screwed up, the motor started, the clutch thrown in by turning the handle 18 and the 50 pump started by throwing up the handle 105. The operation as above outlined and the other steps and adjustments is well within the knowledge of those skilled in the art, particularly that represented by the patents hereinbefore mentioned, and need not be further described. The use of the various 55 packing pieces for the work desired, the calculation of mold blade strokes and the setting of the micrometer rear stop, the use of tables to assist in such calculation, one of which is conveniently placed on the periphery of the setting drum 196 are also well understood and it is therefore thought to be 60

unnecessary to refer in detail to these operations. 65

I claim:

1. A typographic mold comprising type blocks, a cross block, a mold blade, these parts having cavity forming walls, and a 70 base structure provided with a port for admitting molten metal into the mold cavity, said port being adjustable toward and away from said cross block.

2. A typographic mold comprising type 75 blocks, a cross block, a mold blade, these parts having mold cavity forming walls, and a base structure provided with a fixed nozzle opening and thereabove with a movable port for admitting molten metal into 80 the mold cavity, said port being adjustable relatively to said nozzle opening in a direction toward and away from said cross block whereby the stream of incoming metal may 85 be controlled.

3. A typographic mold comprising a base provided with a metal admitting port, and an upper mold structure supported on said base and comprising type blocks, a cross block and a mold blade, said upper structure 90 and said base being relatively adjustable to position the cross block in desired relation to the said port.

4. A typographic mold comprising a base provided with a nozzle opening and a closure 95 abutment and closure slide thereabove to form a metal entrance port and an upper mold structure supported on said base and comprising type blocks, a cross block and a mold blade, said upper structure and said 100 base being relatively adjustable to position the cross block in desired relation to said port.

5. A typographic machine comprising a support, a mold thereon provided with a 105 mold blade, a slidable mold blade carrier, a guide therefor provided with a mold blade stop, said guide being adjustably secured to the support, a mold blade operating lever, a spring-box connecting rod secured at one 110 end to said lever and a system of levers and links connecting the other end of said connecting rod with said mold blade carrier, whereby said system automatically accommodates itself to any adjustment of said 115 guide.

6. A typographic mold comprising a type block, a second type block parallel therewith, a mold blade slidable between said type blocks, a cross block disposed at right angles 120 to said type blocks and slidable from a closed position in which its end abuts said first type block to an open position in which the space between said type blocks is unobstructed thereby.

7. A typographic mold adapted for casting single types or fused strips, comprising type blocks, a mold blade and a cross block,

the side walls of the mold cavity being formed by the inner walls of said blocks and the end wall of said blade, the mold cavity forming walls of said type blocks being extended beyond the cross block and the latter being slidable through an opening in the wall extension of one of said type blocks to a type casting position in which the end of the cross block abuts the said extended inner 5 wall of the other of said type blocks and being slidable from said position to an open or type ejecting position to allow of the ejection of the type by the mold blade between said type block wall extensions, a forward stop for said mold blade whereby the latter may slide forwardly to completely eject the type between said wall extensions and allow the cross block subsequently to slide to its type casting position, whereby 10 single types are produced, an interponent adapted to be positioned before said forward stop whereby the mold blade may move forwardly to eject the type to a position to prevent the cross block sliding to type casting 15 position whereby the rear end of said type forms a wall of the mold cavity and the succeeding cast is fused to said wall, whereby fused strip is produced, yieldable means for operating said mold blade and yieldable 20 means for operating said cross block.

8. A typographic machine comprising a mold, means for injecting molten metal into the cavity thereof, a matrix adapted to seat upon the mold, and means for raising said matrix from seating position and lowering it to and holding it in seating position, said means comprising a rack and pinion, matrix supporting mechanism and a rod mounted eccentrically on said pinion at one end and 35 carrying said supporting mechanism at its other end.

9. A typographic machine comprising a mold having a horizontally movable blade, a vertically movable matrix support having 40 guides extending at an angle to both the horizontal and the vertical, a matrix holder removably mounted in said guides so as to be removed from and inserted therein in the direction of said angle, a matrix removably 45 mounted in said holder and means for moving said matrix from raised position to a position seated on said mold.

10. A typographic machine comprising a mold provided with a mold blade having a 50 forward stop lug thereon, a fixed stop against which said lug is adapted to strike, an interponent adapted to be interposed between said lug and said fixed stop and yieldably driving means for moving said blade 55 forwardly against said fixed stop or said interponent.

11. A typographic machine comprising a mold provided with an adjustable upper structure including a mold blade provided 60 with a stop lug, a stop secured to said struc-

ture, an interponent stop, and means for moving said interponent stop into and out of the path of movement of said stop lug.

12. A typographic machine comprising a mold provided with a mold blade having a forward stop lug, a fixed stop against which said stop lug abuts for stopping an ejecting stroke of the mold blade, an interponent stop, a spring for maintaining said interponent in the path of movement of said stop lug for stopping a fusion stroke of the mold blade, a support for said interponent, a setting device for predetermining the number of revolutions desired, a follower positioned thereby, means connected with a movable part of the machine for moving said follower from the position set, a definite distance for each revolution of the machine, a projection on said support extending into the path of movement of said follower, said follower engaging said projection when the set number of revolutions has been made to move said support and remove said interponent against the action of said spring from the path of movement of said mold blade stop lug, whereby an ejection stroke of the mold blade is produced, means for reciprocating the mold blade forwardly and rearwardly for each machine revolution, means in the path of movement of said ejection stroke of the mold blade for disconnecting said follower from the movable part of the machine operating it, spring means for returning said follower to the set position determined by the setting device, said disconnecting means being released on the rearward movement of the mold blade, whereby the follower is again connected with a movable part of the machine.

13. A typographic machine comprising a mold having a mold plate, yielding means for reciprocating said blade, an adjustable rear stop for arresting the rearward movement of the blade, fusion and ejection stops for arresting the forward movement of the blade, one of said forward stops being movable, manually set selective means for moving said movable stop when the set number of fusion strokes have been made by the blade, to cause an ejection stroke to be made, means connected with a movable part of the machine for driving said selective means a step for each blade stroke and means cooperating with the blade during an ejecting stroke for resetting said selective means.

14. A typographic machine provided with mechanism for producing separated lengths or pieces of typographic strip elements, a portion only of each piece being produced 125 during a single revolution of the machine, and embodying governing mechanism for said producing mechanism, comprising a setting device for predetermining the number of revolutions desired, a follower posi-

tioned thereby, means connected with a movable part of the machine for moving said follower from the position set, said movement being through a definite distance for 5 each revolution of the machine, a trip projection extending into the path of said follower and adapted to be engaged by said fol-

lower when the set number of revolutions has been made, to actuate said trip projection and means operated by said trip projection to control said producing mechanism. 10
